It is therefore possible to obtain a very considerable range of colors by associating a given coupler with a given amine, but—and this is one of the most important features of the invention—it is possible when using a given amine and a mixture of two couplers belonging to two of the Formulae II, III or IV to obtain, by varying the proportions of couplers, all shades between the colors obtained with each of the two couplers used by itself. Similarly, by using a given coupler, a variety of colors can be obtained, although to a smaller degree, by using various amines of the Formula I.

It will be seen that by using a limited number of amines and couplers it is possible to cover the whole range of shades appropriate for hair dyes.

The dyes obtained using the method of this invention have proved to have exceptional resistance to light as compared with dyes hitherto used for hair dyeing. Moreover, a study of the toxicity of the dyes provided by the present invention has shown, contrary to what might have been expected, that they are probably less toxic, and in any case, not more toxic, than the dyes based upon p-phenylenediamine which are at present in use for hair dyeing, which themselves produce appreciable allergy reactions only in extremely rare cases.

Finally, the amines of Formula I have the advantage that they do not impart any color to the hair when applied in the absence of couplers. By virtue of this property, the colors obtained using the present invention result essentially from the combination of the amine and of the coupler and not from the superimposition of two distinct colors, as is the case in the majority of dyeing solutions hitherto employed. This property is most valuable in practice, because it has been observed that the shades obtained in the earlier processes vary from one person to another and even from one place to another on the same hair by reason of a selectivity in the "taking" of the amines and the couplers on the hair, which disadvantage is avoided with the invention since the color obtained results only from the amine-coupler association.

The invention is illustrated by the following examples:

EXAMPLE 1

There is prepared a solution having the following composition:

4-amino-3-methyl-N-ethyl-N-[β -(methylsulphamido)ethyl]aniline sulphate—2.9 g.
2,5-dimethylphenol—1.22 g.
Sodium hydroxide—0.2 g.
Ethyl alcohol—10 cc.
Ammonia solution (22° Bé.)—6 cc.

Water q.s. for 50 cc.

The pH of this solution is 10.5.

The solution, which can be kept without deteriorating, is mixed at the time of use with an equal volume of hydrogen peroxide (20 vol.), and when applied to white hair dyes it blue. The method of dyeing in this and in the following examples consisted of applying the dyeing solution to the hair at ambient temperature, leaving the hair for 20 minutes and then successively rinsing, shampooing, rinsing again and drying.

EXAMPLE 2

There is prepared a solution having the following composition:

4-amino-3-methyl-N-ethyl-N-carbamyl methylaniline sulphate—1.28 g.
3-N-acetamino-6-methyl-phenol—1.65 g.
Ammonia solution (22° Bé.)—6 cc.
Water q.s. for 50 cc.

The pH of this solution is 10.6. When mixed with an equal volume of hydrogen peroxide (20 vol.) and applied to white hair it gives a moderate blue color.

EXAMPLE 3

There is prepared a solution having the following composition:

5 4-amino-N-ethyl-N-carbamylmethylaniline—0.97 g.
4-methoxyphenol—1.25 g.
Ammonia solution (22° Bé.)—6 cc.
Water q.s. for 50 cc.

The pH of this solution is 10.6. When mixed with an 10 equal volume of hydrogen peroxide (20 vol.) and applied to grey hair, it gives a greenish-greyish blue color.

EXAMPLE 4

There is prepared a first solution A having the following composition:

15 N-(4-aminophenyl)morpholine sulphate—2.59 g.
3-acetaminophenol—3 g.
Ammonia solution (22° Bé.)—6 cc.
Water q.s. for 50 cc.

This solution has a pH of 10.6.

There is also prepared a solution B having the following composition:

25 N-(4-aminophenyl)morpholine sulphate—2.59 g.
3-N-(carbamylmethylamino)phenol—2.32 g.
Ammonia solution (22° Bé.)—6 cc.
Water q.s. for 50 cc.

This solution has a pH of 10.6.

30 There are added to 50 cc. of a mixture of these two solutions A and B, 50 cc. of hydrogen peroxide (20 vol.). Depending upon the ratio by volume of the two solutions A and B which have been mixed, there are obtained by dyeing white hair colors which range from purplish blue to light greyish brown.

EXAMPLE 5

There are prepared a solution C, identical to that described in Example 3, and a solution D having the following composition:

40 4-amino-N-ethyl-N-carbamylmethylaniline—0.97 g.
1-phenyl-3-methyl-5-pyrazolone—0.88 g.
Ammonia solution (22° Bé.)—6 cc.
Water q.s. for 50 cc.

45 This solution D has a pH of 10.6.

To 50 cc. of a mixture of these two solutions C and D are added 50 cc. of hydrogen peroxide (20 vol.).

50 Depending upon the proportions of the mixture of C and D, there are obtained upon dyeing grey hair colors ranging from purplish grey to blackish blue. Thus, with 40 volumes of C and 60 volumes of D a dark violet-grey is obtained; with 60 volumes of C and 40 volumes of D a dark bluish-grey is obtained; and with 80 volumes of C and 20 volumes of D a blackish-blue is obtained.

EXAMPLE 6

There is prepared a solution having the following composition:

60 4-amino-3-methyl-N-ethyl-N[β -(methylsulphamido)ethyl]aniline sulphate—2.9 g.
4-benzoylacetaminobenzoic acid—11.3 g.
Ammonia solution (22° Bé.)—25 cc.
Water q.s. for 50 cc.

65 This solution, which has a pH of 10, can be kept well without decomposition. It is mixed with an equal volume of hydrogen peroxide (20 vol.) and applied immediately to white hair, giving a deep orange-yellow color.

EXAMPLE 7

There is prepared a solution having the following composition:

70 N-(4-aminophenyl)piperidine sulphate—2.39 g.
75 1-phenyl-3-methyl-5-pyrazolone—1.75 g.

Ammonia solution (22° Bé.)—8 cc.
Water q.s. for 50 cc.

This solution, which has a pH of 10.7, can be kept well without decomposition. An equal volume of hydrogen peroxide (20 vol.) is added to the solution, and the mixture is applied immediately to white hair giving a dark purplish-red color.

EXAMPLE 8

There is prepared a solution having the following composition:

N-methyl-N-(4'-aminophenyl)- α -aminoacetic acid—
1.8 g.
3-methyl-1-(p-sulphophenyl)-pyrazol-5-one sulphonic acid—2.55 g.

Ammonia solution (22° Bé.)—8 cc.
Water q.s. for 50 cc.

This solution, which has a pH of 10.5, can be kept well without decomposition. By adding thereto an equal volume of hydrogen peroxide (20 vol.) and applying it to white hair, a pale reddish-purple color is obtained.

EXAMPLE 9

There are prepared three solutions E, F and G, each containing:

4-amino-3-methyl-N-ethyl-N-[β -(methylsulphamido)ethyl]aniline sulphate—2.9 g.

and respectively—

For E:
3-acetaminophenol—1.5 g.
Ammonia solution (22° Bé.)—6 cc.

For F:
4-benzoylacetaminobenzoic acid—11.3 g.
Ammonia solution (22° Bé.)—25 cc.

For G:
1-phenyl-3-methyl-5-pyrazolone—1.75 g.
Ammonia solution (22° Bé.)—8 cc.

Each of these solutions is thereafter diluted with water to bring its volume to 50 cc. Two of these solutions are mixed in any proportions and there is added at the time of use a volume of hydrogen peroxide (20 vol.) equal to the volume of this mixture. Depending upon the proportions of the two solutions employed, the following results are obtained on white hair:

E+F: All shades ranging from dark greenish-blue to deep orange-yellow;

F+G: All shades ranging from deep orange-yellow to dark purple-red;

G+E: All shades ranging from purple-red to dark greenish-blue.

EXAMPLE 10

There are prepared a solution H, identical to that described in Example 2, and a solution J containing:

4,4'-dihydroxy-2-aminoazobenzene—0.50 g.

Disodium phosphate (dihydrate)—0.9 g.

Caustic soda q.s. for pH 10.

Water q.s. for 50 cc.

To 50 cc. of a mixture of solutions H and J is added an equal volume of hydrogen peroxide (20 vol.). Depending upon the ratios of the volumes of solutions H and J, there are obtained on application of the mixture to white hair colors ranging from greenish-grey to bright orange-yellow.

EXAMPLE 11

There is prepared a solution K, having the following composition:

4-amino-N-ethyl-N-carbamylmethylaniline—1.93 g.
Solution of ammonia (22° Bé.)—6 cc.
Water q.s. for 100 cc.

The pH of this solution K is 11. This solution is applied to grey hair at ambient temperature and after 20 minutes the hair is then rinsed with water.

There was also prepared a solution L containing:

5 3-acetaminophenol—2.25 g.
Ammonia solution (22° Bé.)—6 cc.
Water q.s. for 100 cc.

The pH of this solution L is 10.6. Solution L is then applied for 20 minutes at ambient temperature to the hair previously treated with solution K, and after 20 minutes the hair is rinsed.

Finally, there is applied at ambient temperature to the hair, treated with solutions K and L, a solution M composed of:

	Cc.
Hydrogen peroxide (50 vol.)	50
Ammonia solution (22° Bé)	6
Water q.s. for 100 cc.	

20 20 minutes after the application of solution M, the hair is rinsed, washed and dried. There is thus obtained a moderate blue color in the hair.

EXAMPLE 12

There is prepared a solution N having the following composition:

3-acetaminophenol—2.25 g.
Ammonia solution (22° Bé.)—6 cc.
30 Hydrogen peroxide (20 vol.)—50 cc.
Water q.s. for 100 cc.

The pH of this solution is 10.6. Solution N is applied to the grey hair previously treated by solution K, as described in Example 11, and the same color is obtained as in Example 11.

EXAMPLE 13

There is prepared a solution containing:

40 4-amino-N-ethyl-N-carbamylmethylaniline—1.93 g.
Solution N of Example 12 q.s. for 100 cc.

Application to grey hair for 20 minutes gives a color identical to that obtained in accordance with Examples 11 and 12.

EXAMPLE 14

White hair is treated by a solution containing:

3- α -(N',N'-diethyl)amino-acetamino-phenol—1.11 g.
Aqueous solution of ammonia at 22° Bé.—6 cc.
50 Water q.s.p. 100 cc.

After 20 minutes, hair is rinsed and treated with another solution containing:

4-amino, 3-methyl, N-ethyl-N-carbamylmethylaniline sulphate—1.28 g.
Aqueous solution of ammonia at 22° Bé.—6 cc.
H₂O₂—6 g.
Water q.s.p. 100 cc.

60 The coloring obtained after 20 minutes is grey-greenish.

EXAMPLE 15

The operation is effected as for Example 14, the first solution being just replaced by the solution as follows:

65 6-methyl-3- α -(N',N'-diethyl)-aminoacetamino phenol—
1.18 g.
Solution of ammonia in water at 22° Bé.—6 cc.
Water q.s.p. 100 cc.

The coloring obtained is grey-greenish.

EXAMPLE 16

A solution is prepared as follows:

4-amino, [N-ethyl,N-(N'-diethyl)-carbamylmethyl] aniline chlorhydrate—1.45 g.

75 6-methyl, 3-(N-carbamylmethyl)amino, phenol—2.22 g.

Aqueous solution of ammonia at 22° Bé.—6 cc.
Water q.s.p. 50 cc.

The pH of said solution is 10.5

Said solution utilized in the same conditions as Example 1 with H₂O₂ produces a dark-blue coloring.

EXAMPLE 17

A solution is prepared as follows:

4-amino, 3-methyl[N-ethyl, N-(N'-diethyl)-carbamylmethyl]aniline chlorhydrate—1.50 g.

3-acetamino, phenol—3 g.

Aqueous solution of ammonia at 22° Bé.—6 cc.
Water q.s.p. 50 cc.

The pH of said solution is 10.6

Said solution applied in the same conditions as for Example 1 with hydrogen peroxide produces a light blue-greenish hue.

EXAMPLE 18

A solution is prepared as follows:

4 - amino,(N-ethyl,N-carbamylmethyl)-aniline chlorhydrate—1.15 g.

3-[(N'-diethyl)-carbamylmethyl]-amino, phenol—2.22 g.

Aqueous solution of ammonia at 22° Bé.—6 cc.

Water q.s.p. 100 cc.

The pH of said solution is 10.6

When said solution is applied in the same conditions as mentioned for Example 2 with hydrogen peroxide, a crimson-grey hue is obtained.

EXAMPLE 19

A solution is prepared as follows:

4 - amino,(N-ethyl,N-carbamylmethyl)-aniline chlorhydrate—1.15 g.

6 - methyl,3 - [(N'-diethyl)carbamylmethyl] - amino, phenol—2.36 g.

Aqueous solution of ammonia at 22° Bé.—6 cc.

Water q.s.p. 100 cc.

The pH of said solution is 10.6.

Said solution applied in the same conditions as mentioned in Example 1 with hydrogen peroxide, a dark crimson-grey hue is obtained.

As shown in the above examples, the method of the present invention is not limited to the application to the hair of a solution containing together the amine, the coupler or couplers and hydrogen peroxide, but includes the successive application of different solutions each containing one or more of the ingredients.

What we claim is:

1. A method of dyeing hair, which comprises the steps of (I) applying to the hair effective dyeing amounts of:

(a) an amine of the formula

in which R₁ is selected from the group consisting of hydrogen, methyl, ethyl and propyl, and X is selected from the group consisting of

(1)

in which R is selected from the group consisting of methyl, ethyl and propyl, and R' is selected from the group consisting of —CH₂CONH₂, —CH₂COOH, —CH₂CH₂NHSO₂CH₃, —CH₂CON(C₂H₅)₂; (2) N-piperidyl; and (3) N-morpholyl;

5

(b) a coupler selected from the group consisting of

in which R₂ represents methoxy,

in which R₃ is selected from the group consisting of —CH₃, —NHCOCH₃, —NHCH₂CONH₂, —NHCH₂CON(C₂H₅)₂

and —NHCOCH₂—N(C₂H₅)₂, and R₄ is selected from the group consisting of hydrogen and methyl;

R₅—CO—CH₂—CO—R₆

in which R₅ is methyl and R₆ is selected from the group consisting of methyl and ethoxy;

(4) R₇—CO—CH₂—CO—R₈

in which R₇ is phenyl and R₈ is selected from the group consisting of p-carboxyphenylamino and m-carboxyphenylamino; and

(5)

in which Y is selected from the group consisting of phenyl, p-sulfophenyl, m-sulfophenyl and 2-chloro-5-sulfophenyl; and

(c) an oxidizing agent;

(II) permitting the mixture of (a), (b) and (c) to remain on the hair for a time sufficient to dye said hair; and

(III) removing the excess of said mixture from the hair.

2. The method as claimed in claim 1, in which the oxidizing agent is hydrogen peroxide.

3. The method as claimed in claim 2, in which the said hydrogen peroxide is applied to the hair in an aqueous solution of the said amine.

4. The method as claimed in claim 2, in which the hydrogen peroxide is applied to the hair in an aqueous solution of the said coupler.

5. A composition of matter for dyeing hair which comprises an aqueous solution having a pH of 9 to 11 and hair coloring amounts of

(a) a colorless amine having the formula

in which R₁ is selected from the group consisting of hydrogen, methyl, ethyl and propyl, and X is selected from the group consisting of

60

(1)

in which R is selected from the group consisting of methyl, ethyl and propyl, and R' is selected from

75

9

the group consisting of $-\text{CH}_2\text{CONH}_2$, $-\text{CH}_2\text{COOH}$, $-\text{CH}_2\text{CH}_2\text{NHSO}_2\text{CH}_3$, $-\text{CH}_2\text{CON}(\text{C}_2\text{H}_5)_2$; (2) N-piperidyl; and (3) N-morpholyl; and

(b) a colorless coupler selected from the group consisting of

(1)

in which R_2 represents methoxy;

(2)

in which R_3 is selected from the group consisting of $-\text{CH}_3$, $-\text{NHCOCH}_3$, $-\text{NHCH}_2\text{CONH}_2$,

$-\text{NHCH}_2\text{CON}(\text{C}_2\text{H}_5)_2$

and $-\text{NHCOCH}_2\text{N}(\text{C}_2\text{H}_5)_2$, and R_4 is selected from the group consisting of hydrogen and methyl;

(3) $\text{R}_5-\text{CO}-\text{CH}_2-\text{CO}-\text{R}_6$

in which R_5 is methyl and R_6 is selected from the group consisting of methyl and ethoxy;

(4) $\text{R}_7-\text{CO}-\text{CH}_2-\text{CO}-\text{R}_8$

in which R_7 is phenyl and R_8 is selected from the group consisting of p-carboxyphenylamino and m-carboxyphenylamino; and

(5)

in which Y is selected from the group consisting of phenyl, p-sulfophenyl, m-sulfophenyl and 2-chloro-5-sulfophenyl.

6. The composition as claimed in claim 5 further comprising an oxidizing agent.

7. The composition as claimed in claim 6, in which the oxidizing agent is hydrogen peroxide.

8. The composition for dyeing hair of claim 5, wherein said amine is selected from the group consisting of 4-

10

amino - 3 - methyl-N-ethyl-N-(β -methyl-sulfamidoethyl)-aniline sulfate, 4 - amino-3-methyl-N-ethyl-N-carbamylmethyl-aniline sulfate; 4-amino-N-ethyl-N-carbamylmethylaniline; 4-amino-N-ethyl - N - carbamylmethylaniline chloride; N-(4-aminophenyl)-morpholine sulfate; N-(4-aminophenyl) - piperidine sulfate; N-methyl-N-(4'-aminophenyl)- β -aminoacetic acid; 4-amino-[N-ethyl-N-(N'-diethyl)-carbamylmethyl]aniline chloride; and 4-amino-3-methyl-[N-ethyl - N - (N' - diethyl)-carbamylmethyl]aniline chloride.

9. The composition for dyeing hair of claim 5, wherein said coupler is selected from the group consisting of 6-methyl - 3 - [(N'-diethyl)carbamylmethyl]aminophenol; 2,5-dimethylphenol; N-acetamino-3-methyl-6-phenol; 4-methoxyphenol; 3-acetaminophenol; 3-N-(carbamyl-methylanino)phenol; 1-phenyl-3-methyl-5-pyrazolone; 4-benzoylacet-aminobenzoic acid; 3-methyl-(1-p-sulfophenyl-pyrazol-5-one) - sulfonic acid; 3-[α -(N'-diethyl)amino]acet - aminophenol; 6-methyl-3-[α -(N'-diethyl)-amino]acetaminophenol; 6 - methyl - 3 - (N-carbamylmethyl)-aminophenol; and 3-[(N'-diethyl)carbamylmethyl]amino phenol.

10. The composition of claim 5 wherein said pH is between 10 and 10.7.
